[57] CLAIM

The ornamental design for a "gun sight," as shown and described.

DESCRIPTION

FIG. 1 is a rear end perspective view showing the new gun sight design;

FIG. 2 is a rear end elevation view thereof;

FIG. 3 is a top plan view thereof;

FIG. 4 is a front end elevation view thereof;

FIG. 5 is a right side elevation view thereof, the left side elevation view being substantially a mirror image thereof; and,

FIG. 6 is a bottom plan view thereof.
